Patented May 11, 1971

220,682

COMBINED PACKAGING TRAY AND COVER

Kenneth W. Artz, Mohnton, Pa., assignor to
W. R. Grace & Co., Duncan, S.C.

Filed Dec. 17, 1968, Ser. No. 15,026

Term of patent 14 years

Int. Cl. D9—04

U.S. Cl. D9—219

FIG. 1

Des. 220,682

PAGE 2

FIG. 2

Des. 220,682

FIG. 3

FIG. 4

FIG. 1 is a top perspective view of a combined packaging tray and cover showing my new design;

FIG. 2 is a top plan view thereof;

FIG. 3 is a sectional view along line 3—3 of FIG. 2; and,

FIG. 4 is side elevational view thereof.

I claim:

The ornamental design for a combined packaging tray and cover, substantially as shown.
